Primary Examiner — Rosemary K Tarcza*Assistant Examiner* — Sanjeev Paul(74) *Attorney, Agent, or Firm* — Albert Bordas, P.A.(57) **CLAIM**

The ornamental design for a home charger, as shown and described.

DESCRIPTION

FIG. 1 is a top plan view of a home charger;

FIG. 2 is a front elevational view thereof, the rear elevational view being a mirror image thereof;

FIG. 3 is a bottom view thereof;

FIG. 4 is a right-side elevational view thereof;

FIG. 5 is a left-side elevational view thereof;

FIG. 6 is a first isometric view thereof; and,

FIG. 7 is a second isometric view thereof, showing my design with its electrical prongs extended.

The claimed home charger is used as an electronic charging device.
